UNITED STATES PATENT OFFICE.

WILLIAM H. COKER, OF MACON, GEORGIA.

IRON FENCE.

SPECIFICATION forming part of Letters Patent No. 383,343, dated May 22, 1888.

Application filed September 14, 1887. Serial No. 249,600. (No model.)

To all whom it may concern:

Be it known that I, WILLIAM H. COKER, a citizen of the United States, residing at Ma-
5 con, in the county of Bibb and State of Geor-
gia, have invented certain new and useful Im-
provements in Iron Fences, of which the fol-
lowing is a specification, reference being had
therin to the accompanying drawings, in
which—

10 Figure 1 is a side and sectional view of the simple strip particularly adapted for fence-
pickets. Fig. 2 is a like view of a compound
strip adapted for use as a fence-rail. Fig. 3 is
15 a like view of a compound strip adapted for
use as a fence-post. Fig. 4 is an enlarged sec-
tion of Fig. 1, showing a slightly different con-
struction. Figs. 5 and 6 are sectional views
20 of different forms of posts. Fig. 7 shows the
invention applied to a fence. Fig. 8 is a sec-
tional view of the fence, showing one of the
brace-rods. Figs. 9 and 10 are respectively a
25 side elevation and sectional plan view of a
foot-block for a post. Fig. 11 is a view illus-
trating the manner of attaching the fence-rail
25 to the post.

My invention has for its objects to provide
an extremely light and durable metallic fence,
which will at the same time be highly orna-
30 mental in appearance and very strong and sta-
ble when once erected, as will be fully under-
stood from the following description and claims
when taken in connection with the annexed
drawings.

The strip A shown in Figs. 1 and 4, and on
35 which the construction of all the other parts
is based, has three equidistant radial arms or
flanges of equal or unequal lengths in cross-
section. The strip may be rolled into form,
and may be solid or formed of sheet metal or
40 otherwise constructed. The preferred method
of constructing these strips (which are used as
pickets in the fence) so as to make them light
and inexpensive is to form them out of a sin-
gle strip of sheet metal cut the required width
45 and bent and folded upon itself, and pressed
into shape by suitable dies or formers, the con-
tiguous faces of the metal being pressed closely
in contact, as shown clearly in Fig. 1. The
construction of the strip is such, as will be evi-
50 dent from the drawings, that a strain from any
direction will be resisted by one of the flanges

in an edgewise direction or by two of the flanges
meeting in V shape, either of which strongly
resists departure from their normal shape.

In Fig. 2 is shown a fence rail, B, formed of 55
two strips, A A, having two of the flanges
joined together, so as to form a web, C, with
V-shaped ends, which may have variously-
shaped pieces punched out of it, as plainly
50 shown in the plan, Fig. 2.

The apertures or slots made in the webs of
the rails are similar in shape to the pickets,
and are for the purpose of receiving them, the
pickets being forced into the slots, which are
65 cut so as to fit the pickets snugly and hold them
in place in the rails. The ends of these rails
are also slotted for the purpose of receiving
the flanged vertical edges of the posts, the slots
60 being cut to fit and clamp the webs of the posts
tightly and be thereby supported. 70

In Figs. 3 and 5 several strips A, with one
of the flanges of each elongated and all joined
at a common center, are used to form a fence-
post with a multiple-part web.

In Fig. 6 two rails such as shown in Fig. 2 75
are joined at the center of the web by rivets
or otherwise to form a compound web, and
the ends, bent outward, forming a strong post
or rail.

The rails and posts are all preferably con- 80
structed in a similar manner to the pickets A—
that is, are formed of strips of sheet metal cut
to a suitable width and folded longitudinally,
and pressed into shape by dies or formers, the
contiguous faces of the metal being pressed 85
closely together.

In Figs. 9 and 10 is shown a bed-block for
the posts, which consists of a base-plate, D,
having lugs or standards E raised thereon to
embrace the webs of the posts and be firmly
90 secured thereto by bolts or otherwise. These
blocks may be secured to a coping, F, (shown
in Figs. 7 and 8,) or be fastened in any other
manner to firmly support the fence-posts.

The fence may be further supported by brace- 95
rods G, one end of which may pass through
one of the rails B.

In putting the fence together the posts first
receive the rails, and then the pickets are in-
serted through the holes prepared for them; 100
or the rails and pickets may be placed together
before being secured to the posts; but in either

case, or after the entire panel or panels are put together, they are dipped in acid, and then in a galvanizing material to galvanize and cement them together. However, other fluids or processes may be used, the fence, or part thereof, being put together before being treated. The galvanizing material closes the joints and solders the pickets and rails together.

In addition to the advantages of strength, 10 lightness, and cheapness possessed by the constructions described may be mentioned that of ornamentation, as a fence even in its simplest form, as shown in Figs. 1, 2, and 3, will present a pleasing appearance.

15 It will be understood that ornaments of various kinds may be applied to different parts of the fence, and that other forms and modifications than those shown may be used.

It will be perceived that an essential feature 20 of my invention consists in so slotting the ends of the horizontal rails that they will embrace the flanged radial wings of the posts, the slots in the ends of the rails being of such a width that they will, when the rails are forced to the 25 proper position on the posts, closely and firmly clamp the radial flanged wings of the same. By this construction the rails will not only be supported by the posts, but they will be securely attached to them, thus insuring a very 30 strong and firm fence when the panels are all connected together and erected, as is evident. The galvanizing material will serve to further secure the parts of the panel in position.

Having described the invention, what I claim 35 is—

1. The metallic fence-panel herein described, consisting of the posts provided with radial flanged wings, the horizontal rails each consisting of a web provided on its longitudinal 40 edges with two diverging flanges, the ends of the said rails being provided with slots, which are cut to embrace and closely clamp the radial flanged wings of the posts in the manner described, whereby the said rails are supported

by the posts and securely attached thereto, 45 and the three-winged pickets supported by the said rails, substantially as described.

2. A fence-post consisting of the longitudinal radial wings, each of the said wings being provided on its longitudinal edge with two diverging flanges, the said post being constructed of sheet metal bent longitudinally and folded upon itself, as shown, the contiguous faces of the metal being pressed into intimate contact, 50 substantially as described.

3. The herein-described fence-rail, consisting of a strip of metal bent longitudinally and folded upon itself with its contiguous surfaces pressed closely in contact, the sheet being so bent as to form a web, C, provided on its longitudinal edges with two diverging flanges equidistant from each other and the web, 55 substantially as described.

4. The herein-described metallic fence-panel, consisting of the posts constructed of radial 60 wings, the longitudinal edges of which are each provided with two diverging flanges, the rails B, each consisting of a web, the edges of which are also provided with two longitudinal diverging flanges, the webs of the said rails being punched or perforated for the reception of the pickets and slotted at their ends to engage or embrace the flanged edges of the radial wings of the post, and the pickets inserted in the perforations in the webs of the rails, and 65 each consisting of three radial wings equidistant from each other, the several parts of the panel being constructed of strips or sheets of metal bent longitudinally and folded upon themselves with their contiguous faces pressed 70 into intimate contact, all arranged substantially as herein described.

In testimony whereof I affix my signature in presence of two witnesses.

WILLIAM H. COKER.
